UNITED STATES PATENT OFFICE

LOUISE GROM, OF NEW YORK, N. Y.

SANITARY MANICURING TOWEL

Application filed September 13, 1928. Serial No. 305,703.

My invention relates more particularly to an improved sanitary manicuring towel having one portion of its length composed of crepe paper and an intermediate portion of a combination of fabric and paper on top of one another, and the other end portion of fabric, so that all of the portions united together form a single towel.

An important object of my invention is to 10 provide a towel which is sanitary and sufficiently cheap in construction cost so that it may be thrown away after a single use.

The present practice of manicurists is to use a towel formed entirely of a fabric. This 15 practice has been found to be unsanitary for the reason that such towels are apt to absorb and hold even when laundered bacterial matters, short hairs and the like with the result that when used, they frequently infect 20 the cuticle of a person by such bacterial matters, or force the short hairs not removed from such towels, under the cuticle and so as to form ulcerations upon the user thereof. Further, the cost of washing such towels is 25 greatly in excess of the cost of producing the towels made in accordance with my invention.

With this and other objects in view which will appear as the description proceeds, the 30 invention resides in the novel combination and arrangement of parts hereinafter more particularly pointed out and claimed, it being understood that minor changes may be made within the scope of what is claimed 35 without departing from the spirit or sacrificing any of the advantages of the invention.

The accompanying drawings will serve to 40 illustrate my invention.

Figure 1 is a perspective view of a continuous piece of crepe or absorbent paper.

Figure 2 is also a perspective view of a hand towel.

Figure 3 is a perspective view of the invention, having combined Figure 1 with that of Figure 2, so that a sanitary manicuring towel is formed thereby.

Figure 4 is a side view of Figure 3.

Figure 5 is a fragmentary portion of Fig-

ure 3 showing the parts enlarged or exaggerated.

Like reference characters refer to like members in the various figures.

Referring now more particularly to the drawings, this invention comprises a continuous piece of crepe or absorbent paper 10, being preferably twenty five inches in length and fifteen inches in width, as shown in Figure 1, or any other desirable soft paper, 60 being of a continuous piece.

Figure 2 is a hand towel which consists of a doubled layer of fabric, gauze or cheesecloth 11 and 12, rectangular in configuration, and upon one side thereof a piece of crepe or absorbent paper 13 is stitched thereon by means of stitchings 14, so that a cheesecloth flap 15 will extend crosswise thereof. The whiting bleach cord 16 is enclosed in the extreme marginal lapped over end of the flap, 70 which cord is particularly adapted for the cleaning of nails by manicurists when the same is operated as described hereinafter. However, it is to be understood that this whiting bleach cord 16 may be eliminated 75 wherever it is not desired or essential in any of the figures shown. The hand towel shown in Figure 2 is finished off on three sides so that the same will present a neat appearance.

Figure 3 is an illustration of the sanitary 80 manicuring towel combining Figure 2 together with that of Figure 1. It will be noticed that in Figure 3 the absorbent paper 10 is of a continuous piece so that a portion 85 thereof extends crosswise as at 17, this end being but of a single layer. The intermediate portion of this towel comprises four layers, two of which layers are of cheesecloth 11 and 12, (being doubled over upon each other) and the other two layers of which are of 90 paper 13 and 10. The crosswise flap 15 is of course a continuation of the doubled layers of cheesecloth 11 and 12 and in the marginal end thereof the whiting bleach cord is 95 enclosed in the same manner as in Figure 2.

In order to make the towel as shown in Figure 2 especially suitable as a sanitary napkin for women, it should be clearly understood that layer 13 in such an instance is comprised of wadding sheet material (manufactured 100

cloth) backed by an absorbent paper. Likewise the same applies to Figure 3 when this form is desired to be used as a sanitary napkin for women; however, when so used for this purpose, it is to be understood that the whiting bleach cord 16 may be entirely eliminated.

In use, the sanitary manicuring towel (Figure 3) is laid over a support by the manicurist, such as a pillow or rail with the paper portion towards the person whose nails are under treatment, and the flexible portion of the fabric and paper combined is nearer to the operator. In using the sanitary manicuring towel, the operator handles the fabric and combined side as in the manner of any towel, to wipe out the nails, push back the cuticle and the like, and to whiten and bleach the nails underneath with the flexible gauze flap, the foregoing being a great time saver for the manicurist. The bottom of the flexible flap is used by the manicurist especially when the flap is provided with the whiting bleach cord, by sliding it back and forth underneath the nails which, as a result thereof, it will be seen, the cleaning operation of that portion of the nails is well accomplished. The paper portion may be used by the person whose nails are under treatment, such as to dry the hands, etc. and after the manicuring operation is completed, the towel is thrown away or otherwise destroyed.

Various changes may be made without departing from the spirit of the invention, for example, instead of uniting the crepe or absorbent paper together with the fabric, cloth or gauze by means of stitching, means might be devised whereby such uniting might be accomplished by means of weaving them together in the process of the manufacture of the paper and gauze, or cloth, to form a towel.

It is further to be understood that I do not limit myself on length, width, thickness of the cheesecloth, fabric, or substitutes upon the paper or paper substitutes forming the hand towels, or manicuring towels, nor do I limit myself on the length, width or thickness of the sheet wadding utilized in connection with the sanitary napkin for women as previously set forth.

Having thus described my invention what I claim as new and desire to secure Letters Patent upon is:—

1. A manicure towel, one portion thereof being formed of absorbent paper, another portion thereof being formed of gauze material, a portion of said gauze material being united with said absorbent paper, a flap of gauze strip, said flap being an extension of the first mentioned gauze material.

2. A manicure towel, one portion thereof being formed of crepe paper, another portion thereof being formed of fabric material, the greater portion of said fabric material being united with said crepe paper, a flexible flap of

fabric strip, said flexible flap being a crosswise extension of the first mentioned fabric material.

3. A manicure towel, one portion thereof being formed of crepe paper, another portion thereof being formed of fabric material, the greater portion of said fabric material being united with said crepe paper, a flexible flap of fabric strip, said flexible flap being a crosswise extension of the first mentioned fabric material; a whiting bleach cord located in and near the marginal border of said flexible flap.

4. A hand towel, one portion thereof being formed of crepe paper, another portion thereof being formed of fabric material, a portion of said fabric material being united with said crepe paper, a flap of fabric strip, said flap being an extension of the first mentioned fabric material.

5. A hand towel, one portion thereof being formed of crepe paper, another portion thereof being formed of fabric material, the greater portion of said fabric material being united with said crepe paper, a flexible flap of fabric strip, said flexible flap being a crosswise extension of the first mentioned fabric material.

6. A hand towel, one portion thereof being formed of absorbent paper, another portion thereof being formed of gauze material, the greater portion of said gauze material being united with said absorbent paper, a flexible flap of gauze strip, said flexible flap being a crosswise extension of the first mentioned gauze material, a whiting bleach cord located in and near the marginal border of said flexible flap.

In testimony whereof I affix my signature.

LOUISE GROM.
